SHANK TAPING MACHINE

Robert C. Sadler, Portsmouth, Ohio, assignor to
The Selby Shoe Company, Portsmouth, Ohio,
a corporation of Ohio

Application December 8, 1947, Serial No. 790,245

9 Claims. (Cl. 12—60)

1

This invention relates to a machine for wrapping tape or the like, about metal, wood, or plastic rods or bars. More particularly, it relates to a machine for wrapping gummed tape about metal shank stiffeners of the type employed in strengthening the central or shank portion of shoes.

The use of metal pieces to strengthen the shank portion of a shoe is known. It often is desirable to wrap a metal shank stiffener with gummed cloth or other material which may be previous to the cements employed in shoe manufacture before the stiffener is assembled in a shoe so that the shank stiffener may be firmly and permanently cemented in the shank portion of a shoe. It is also desirable to wrap a metal shank stiffener with gummed cloth or other material so that the metal shank stiffener will not squeak when the shoe is worn.

Hand wrapping of metal shank stiffeners is inconvenient and tedious, and it has been a principal objective of the present inventor to provide a machine which automatically wraps gummed tape about a metal shank stiffener.

A further objective of the inventor has been to provide a machine which automatically cuts off from a strip of gummed tape, the amount of tape necessary for wrapping a shank stiffener and then wraps the tape about a shank stiffener.

Briefly, the machine of this invention includes a folding mechanism for wrapping tape about a stiffener and a cut-off device which severs lengths of tape from a roll of tape prior to wrapping. The folding mechanism comprises a pad of soft, pliable material such as foam or sponge rubber, upon which a length of gummed tape is placed with a shank stiffener upon it. Hinged side pieces, which hold the sponge rubber block, bend inwardly to deform the rubber and cause it to surround the tape and shank stiffener to wrap the tape firmly about the stiffener. The gummed tape is supplied from a roll, and a length of tape is preferably cut from the roll prior to folding about a stiffener. The cut-off mechanism is located between the roll of tape and the sponge rubber block of the folding mechanism. It consists of a knife for severing lengths of tape and a linkage which lowers the knife against a shear plate to make a cut. Interconnections between the cut-off device and folding mechanism operate them sequentially so that a length of gummed tape is first cut from the strip and then automatically wrapped about a shank stiffener.

In the following detailed description the invention will be described with particular refer-

2

ence to a machine for wrapping gummed tape about shank stiffeners, but it will be readily apparent to those skilled in the art that the machine is adaptable for use in wrapping gummed tape and the like about wood or plastic rods or staffs of various kinds as well as metal shank stiffeners, and that the machine can be used for wrapping various types of tapes although it is particularly intended for wrapping adhesively coated tape about shank stiffeners for shoes.

Other objects and further advantages of the machine will be more fully apparent from a description of the drawings in which:

Figure 1 is a side elevational view of a shank covering machine constructed in accordance with this invention.

Figure 2 is a plan view of the machine illustrated in Figure 1.

Figure 3 is an enlarged sectional view taken along the line 3—3 in Figure 1, showing the details of the cut-off device and illustrating the device in position at the start of a cut-off stroke.

Figure 4 is a sectional view taken along the same line as Figure 3 but showing the cut-off device in its position at the end of a cut.

Figure 5 is an enlarged perspective view showing the details of the folding mechanism and illustrating the mechanism at the start of the folding stroke.

Figure 6 is a sectional view taken along the line 6—6 in Figure 5.

Figure 7 is a perspective view showing the folding mechanism after it has moved partially into operative position.

Figure 8 is a sectional view taken along the same line as Figure 6 but showing the folding mechanism at the end of the folding operation.

Figure 9 is a schematic view showing the position of the actuating chains when the machine is not acting on the work.

Figure 10 is a schematic view showing the actuating chains at the end of an operation.

Figure 11 is an enlarged sectional view taken along line 11—11 in Figure 3 showing details of the rocker bar which operates the cut-off device.

Figure 12 is an enlarged sectional view taken along line 12—12 in Figure 5 showing details of the slotted connection between the parts of the folding mechanism.

As illustrated in Figures 1 and 2, a machine for wrapping shank stiffeners, constructed in accordance with this invention, is shown mounted on a table 10. A main supporting base 11 is attached to the table 10 by a series of angles 12 which are attached by screws to the table 10.

and base 11. The left-hand end 13 (as shown in Figures 1 and 2) of the base 11 extends beyond the edge of the table 10 while the remainder of the base rests on the table 10.

A roll of gummed tape 14 is supported on a tape carrier 16 of usual design, which in turn, rests on the right-hand portion of the base 11. The tape carrier includes a pair of side members 17 which define a channel 18 along which tape from the roll 14 is directed. A guide 19 keeps the tape in the guide channel 18. The roll 14 is carried by an axle 20, the ends of which are contained in slots 21 at the right-hand end of the channel 18. A small pad of sponge rubber 22 forms part of the channel 18 at its left-hand end, and the tape passes over the pad 22.

A block 23 of sponge rubber, or the like, is supported in the overhanging end 13 of the base 11, and the block 23 is located a short distance beyond the left-hand end of the channel 18 so that tape from the roll 14 can be pulled along the channel 18 and directly over the block 23. Details of construction of the block 23 can best be seen by reference to Figures 5-8 inclusive. The block is preferably made of foam or sponge rubber or other similar elastic material, which may readily be deformed by pressure but which rapidly regains its original shape when the pressure is removed. In its normal position, the block is rectangular in vertical cross-section as shown in Figures 5 and 6. The outer edges of the lower side of the block 23 rest on the base 11, and the portion of the base 11 which underlies the central portion of the block 23 is cut away as shown at 24 to permit the block to expand downwardly when deformed, as shown in Figure 8.

Hinged side plates 26 on opposite sides of the sponge rubber block 23 hold it in place. The plates 26 are attached by screws 27 to the upper halves of hinges 28, while the lower halves of the hinges 28 are attached by screws 29 to the base 11. Integrally formed with the side plates 26 are adjacently disposed front plates 31 and 32 attached respectively to the left and right hand plates 26. The front plate 31 has a tongue 33 extending beyond the right-hand side plate 26. A chain 34, which operates the hinged plates, is linked in an opening 36 in the end of the tongue. The plate 32, on the other hand, is disposed flush against the inner side of the plate which includes the tongue 33 and reaches only partly across the front of the block 23. The plate 32 includes a slot 37 at an angle of 45 degrees to the horizontal, and, as shown in Figure 12, a bolt 38 fits through the slot 37 and a bore 39 in the front plate 31 to link the plates 31 and 32. A bearing sleeve 41 surrounds the bolt 38. The slotted connection between the front plates 31 and 32 forces both side plates to turn inwardly together when the chain 34 is pulled downwardly, as shown in Figure 7.

When the chain 34 is pulled downwardly, the block 23 is deformed passing successively through the stages shown in Figures 6, 7 and 8. Prior to deformation, a length of tape 42 having its gummed side up, is positioned upon the block 23 and a shank stiffener 43 is laid upon the length of tape. Then, as the chain 34 is lowered, the sponge rubber of the block is deformed until it completely envelops the tape 42 and stiffener 43, wrapping the tape about the stiffener.

Prior to being wrapped about the stiffener 43 the length of tape 42 should be severed from the tape in the channel 18, and a cut-off device indicated generally at 44 is positioned between

the channel 18 and the block 23. Operation of the cut-off device 44 is shown in Figures 3 and 4. It includes a cut-off blade 46 pivotally mounted on a plate 47 on a pivotal connection 48 near the center of the blade 46. The plate 47 is welded or otherwise permanently attached in a vertical position to the left-hand end (Figure 2) of the tape carrier 16 and forms a surface against which the blade 46 shears lengths of tape from the roll 14. The blade 46 is swung by a rocker bar 49 which is pivoted to the plate 47 by a pivot 51 near the center of the rocker bar. Details of the pivotal connections are shown in Figure 11. A pin 52 attached to and extending from the left-hand end of the rocker bar 49 bears against the lower left-hand side of the blade 46 (Figure 3). A chain 53 is attached to the right-hand end 54 of the rocker bar 49. The base 11 is cut away as shown at 55 to allow room for rotation of the rocker bar 49. The chain 53 passes downwardly from the rocker bar 49 over a pulley 56 carried by a bracket 57 which bracket is attached to the lower side of the base 11 (Figures 3 and 4). When the chain 53 is pulled downwardly, the rocker bar 49 is rotated about the pivot 51 and the pin 52, bearing against the underside of blade 46, forces the blade to rotate into cutting position. The right-hand end of the blade 46 is hollow ground or otherwise sharpened to give a sharp cutting knife edge which cooperates with the upper edge of the plate 47 when the blade 46 is rotated into cutting position. A stop 58 limits the travel of the blade 46, and a spring 59 connected between the left-hand end of the blade 46 and the pulley bracket 57 raises the knife edge from its cutting position when the pull on the chain is released.

As shown in Figure 1, both the chain 34, which operates the folding section of the machine and the chain 53, which operates the cut-off device, are connected to a treadle 61. However, the chain 34 is sufficiently long that it is slack, as indicated at 62, when the chain 53 is taut. The chain 53 includes a spring 63 which expands after the blade 46 has come to rest against the stop 58 so that the chain 34 can operate the folding mechanism after the cut-off device has severed a length of tape. The treadle 61 is a simple, foot operated treadle, an end of which is connected to a floor 64 by a hinge 66. The chains 34 and 53 are attached to the treadle 61 by a ring 67 intermediate its ends; and, at the end of the treadle opposite the hinge 66, a foot pedal 68 is provided for the operator of the machine.

The operation of the machine is shown clearly by the drawings and can be explained simply by reference to the Figures 9 and 10, which show schematically the sequential operation of the parts of the machine, and by reference to the other drawings. When the machine is to be operated, tape from the roll 14 (Figures 1 and 2) is fed along the channel 18 under the guide 19 and over the rubber pad 22. A shank stiffener 45 is pressed down on the tape over the pad 22 to adhere to the tape, and then the tape is pulled through the cut-off device 44 until it is positioned upon the block 23. The stiffener and tape are placed on the block 23 as shown in Figures 5 and 6, and then the treadle 61 is depressed to operate the cut-off device. (See Figures 9 and 10.) Only after the blade 46 has descended against the stop 58 to complete a cut, the spring 63 in the chain 53 expands as the treadle 61 is further depressed and the chain 34 is brought

into operation to swing the hinged side plates 26 about the sponge rubber block 23 to deform the block as shown in Figures 6, 7 and 8. Opposite upper edges of the block 23 are forced together by the plates 26 until the block 23 completely surrounds and envelops the stiffener 43 and the length of tape 42 to wrap the tape about the stiffener. Then pressure is released from the treadle 61 and the springs 59 and 63 raise the treadle 61 and knife blade 46 while the natural resilience of the sponge rubber block 23 causes it to regain its original shape. The adhesive on the tape holds it about the stiffener 43 and the wrapped stiffener can be removed from the machine.

Although this invention has been described with particular reference to the wrapping of flat metal shank stiffeners it should be immediately clear that the machine of this invention is readily adaptable for wrapping other types of rods or staffs having either a rounded or flat cross section. The description has been directed to the use of a tape which is adhesive on one side, but if desired, a tape free from adhesive could be employed together with a stick or rod having an adhesive coating. Many other modifications will be apparent, and it is not intended that the invention be limited by the foregoing disclosure of a preferred embodiment except as pointed out in the appended claims.

Having described my invention, I claim:

1. A machine for wrapping tape about a staff which comprises a block of readily pliable elastic material, hinged side members on opposite sides of said block, means for positioning a strip of tape upon said block with the staff upon said strip, the staff and strip being positioned parallel to the hinged side members, and means for swinging inward the hinged members to deform the block and cause the block to envelop the staff and tape, whereby the tape is wrapped about the staff.

2. A machine for wrapping adhesively surfaced tape about a staff which comprises a block of sponge rubber, hinged side members on opposite sides of said block, means for positioning a strip of tape upon said block adhesive side up with the staff upon said strip, the staff and strip being positioned parallel to the hinged side members, and means for swinging inward the hinged members to deform the block and cause the block to envelop the staff and tape, whereby the tape is wrapped about the staff.

3. A machine for wrapping tape having an adhesive surface about a staff which comprises a block of readily pliable elastic material, side members on opposite sides of the block, means for positioning a strip of tape upon said block adhesive side up with a staff upon said strip of tape, the staff and tape being positioned parallel to the hinged side members, a cutting blade for severing lengths of tape, and means for sequentially operating said cutting blade and for swinging inward the hinged side members to deform the block and cause the block to envelop the shank stiffener and tape, whereby a length of tape is cut from the strip and wrapped about the staff.

4. A machine for wrapping tape having an adhesive surface about a staff which comprises a block of sponge rubber, hinged side members on opposite sides of the block, a roll of tape, means for guiding a strip of tape from said roll to position the free end of said strip of tape upon said block adhesive side up with a staff upon said

tape, the staff and tape being positioned parallel to the hinged side members, a cutting blade for severing lengths of tape located between said roll and said block, and means for sequentially operating said cutting blade to sever a length of tape and for swinging inward the hinged side members to deform the block and cause the block to envelop the shank stiffener and tape, whereby a length of tape is cut from the strip and wrapped about the staff.

5. A machine for wrapping tape having an adhesive surface about a shank stiffener for a shoe which comprises a block of sponge rubber, hinged side members on opposite sides of the block, a roll of tape, means for guiding a strip of tape from said roll to position the free end of said strip of tape upon said block adhesive side up with a shank stiffener upon said tape, the shank stiffener and tape being positioned parallel to the hinged side members, a cutting blade for severing lengths of tape located between said roll and said block, and means for sequentially operating said cutting blade to sever a length of tape and for swinging inward the hinged side members to deform the block to envelop the shank stiffener and tape, whereby a length of tape is cut from the strip and wrapped about the shank stiffener.

6. A machine for covering a shank stiffener for a shoe with tape, which machine comprises, a roll of absorbent tape, said tape having a coating of adhesive on one side, means for rotatably supporting said roll, guide means for guiding a strip of tape from said roll along a pathway; a vertical metal shear plate attached to said guide means at the end thereof away from said roll, a block of sponge rubber spaced from said shear plate, hinged side members on opposite sides of said block, said hinged side members being mounted parallel to the centerline of said pathway, whereby tape from said pathway is guided over said block and parallel to said hinged side members, a cutting blade located between said roll and said block, said cutting blade cooperating with said shear plate to sever lengths of tape, and means for sequentially operating said cutting blade and for swinging inward said hinged side members to force opposite upper edges of said block together, whereby said cutting blade severs a length of tape from said strip and then said block is deformed so that the tape and a shank stiffener mounted thereon are enveloped by the block to wrap the tape about the shank stiffener.

7. A machine for covering a shank stiffener for a shoe with tape, which machine comprises, a source of absorbent tape, said tape having a coating of adhesive on one side, guide means for guiding a strip of tape from said source along a pathway; a vertical metal shear plate attached to said guide means at the end thereof away from said roll, a block of readily deformable plastic material spaced from said shear plate, hinged side members on opposite sides of said block, said hinged side members being mounted parallel to the centerline of said pathway, whereby tape from said pathway is guided over said block and parallel to said hinged side members, a cutting blade located between said roll and said block, said cutting blade cooperating with said shear plate to sever lengths of tape, and means for sequentially operating said cutting blade and for swinging inward said hinged side members to force opposite upper edges of said block together, whereby said cutting blade severs a length of tape from said strip and then said block is de-

formed so that the tape and a shank stiffener mounted thereon are enveloped by the block to wrap the tape about the shank stiffener.

8. A machine for covering a shank stiffener for a shoe with tape, which machine comprises, a source of absorbent tape, said tape having a coating of adhesive on one side, guide means for guiding a strip of tape from said source along a pathway, a block of readily deformable plastic material spaced from said pathway, hinged side members on opposite sides of said block, said hinged side members being mounted parallel to the centerline of said pathway, whereby tape from said pathway is guided over said block and parallel to said hinged side members, a cutting device for severing lengths of tape located between said pathway and said block, and means for sequentially operating said cutting device and for swinging inward said hinged side members to force opposite upper edges of said block together, whereby said cutting device severs a length of tape from said strip and then said block is deformed so that the tape and a shank stiffener mounted thereon are enveloped by the block to wrap the tape about the shank stiffener.

9. A machine for covering a shank stiffener for a shoe with tape, which machine comprises, a roll of absorbent tape, said tape having a coating of adhesive on one side, means for rotatably supporting said roll, guide means for guiding a strip of tape from said roll along a pathway, a vertical metal shear plate attached to said guide means at the end thereof away from said roll, a pad of sponge rubber under said pathway ad-

acent to said shear plate providing a resilient support for the tape for applications of a shank stiffener prior to severance of the tape, a block of sponge rubber on the opposite side of said shear plate in spaced relation therefrom, hinged side members on opposite sides of said block, said hinged side members being mounted parallel to the centerline of said pathway, whereby tape from said pathway is guided over said block and parallel to said hinged side members, a cutting blade located between said pad and said block, said cutting blade cooperating with said plate to sever lengths of tape, and means for sequentially operating said cutting blade and for swinging inward said hinged side members to force opposite edges of said block together, whereby said cutting blade severs a length of tape from said strip to leave a free end of tape upon said pad, and then said block is deformed so that the tape and a shank stiffener mounted thereon are enveloped by the block to wrap the tape about the shank stiffener.
